Stanley Roth, Scarsdale, N. Y., assignor to Stanley Roth, Julius B. Sheftel, and John Earl
Van Eenenaam, copartners doing business as
R. S. V. Company

Application December 20, 1939, Serial No. 89,023

Term of patent 3½ years

To all whom it may concern:

Be it known that I, Stanley Roth, a citizen of the United States, residing at Scarsdale, in the county of Westchester and State of New York, have invented a new, original, and ornamental Design for a Game Board, of which the following is a specification, reference being had to the accompanying drawing, forming a part thereof.

The figure is a plan view of a game board showing my new design.

The article is of no appreciable or substantial thickness.

I claim:

The ornamental design for a game board, as shown and described.

STANLEY ROTH.
